UNITED STATES PATENT OFFICE

NIIS M. ROSENDAHL, OF WATERLOO, IOWA, ASSIGNOR TO CONSTRUCTION MACHINERY COMPANY, A CORPORATION OF IOWA

CONCRETE DISTRIBUTOR

Application filed April 10, 1926. Serial No. 101,010.

This invention relates to distributing buckets for concrete mixers and has special reference to one adapted for use upon a concrete mixer for street paving and the like.

5 The principal object is to provide novel means whereby the bucket may be operated in either direction opened or closed.

Another object is that of convenient regulation of the door opening, and installing the door in such a manner as to act as a spreader and obviate the necessity of a special device for such purpose.

Other objects and advantages of the invention will appear in the further description 15 thereof.

Referring now to the accompanying drawings, forming part of this application, and wherein like reference characters indicate like parts:

20 Figure 1 is a diagrammatic elevation of the paver boom and the operable mechanism associated therewith;

Figure 2 is an elevation of the operating mechanism taken at right angles to Figure 1;

25 Figure 3 is a section on the line 3—3, Figure 5;

Figure 4 is a bottom plan view of the discharge end of the bucket showing the doors thereof closed;

30 Figure 5 is an elevation at right angles to Figure 3 of the bucket suspension;

Figure 6 is an elevation of the cushion cross-head in the bucket suspension; and

35 Figure 7 is a view similar to Figure 3, except that the bucket 3 is shown in its open position with one door thereof in position to act as a spreader.

1 represents the boom, which is, in this illustration, shown as being composed of two 40 spaced channel bars back to back, and in which channel bars the bucket carriage is reciprocally mounted as upon the wheels 2, the carriage being illustrated at 3.

The boom 1 is pivotally mounted as at 4 upon the forward frame portion 5 of the paver, while the outer end of the boom is as is customary supported by a tackle 6 operating in the sheave 7 adjacent the outboard end of the boom or jib.

50 The bucket operating mechanism is illus-

trated at 8, the same, as a preferred form of construction, comprising the drive shaft 9 upon which the two frictionally driven drums 10 and 11 are mounted and operated by the clutch lever 12 being pivoted at 13' for alternate engagement with the drums, or capable of neutral position when neither drum is operated. There is also provided a foot band brake 13 for either drum each having a pedal 14 for engagement by the foot of the operator. The pulling out cable is illustrated at 15, it being wound about the drum 10 and passing over a sheave mounted on the shaft 16 near the pivotal end of the boom and also about the sheave 17 in the free end of the boom, then back to its permanent connection at 18 about the sleeve of the transverse shaft 19 in the bucket carriage 3, so that any draft inwardly upon the cable 15 tends to draw the bucket carriage and bucket outwardly. 70

The bucket return line is illustrated at 20, passing over any convenient arrangement of sheaves in the paver, over a sheave on the shaft 16 near the heel of the boom, thence to and about the sheave 21 mounted upon the 75 shaft 19 in the bucket carriage, and backwardly to where it is pivotally fixed as at 22 to the crosshead trigger 23 mounted upon the shaft 24 in the carriage 3 intermediate of the bucket arms 25. In the notched center of the 80 crosshead trigger 23 and upon the shaft 24 is slung one end of the chain 26, the opposite end being attached to the transverse shaft 27 in the upper end of the links or arms 28 which control the bucket doors. This shaft 27 also controls the outer end of the lever 29 which is pivoted upon the transverse shaft 30 in the carriage frame in the depending portion 31 of the carriage frame, the chain 26 acting as a limiting device or snubber to the 90 throw of both the lever 29 and the bucket doors.

The lower end of the lever 29 has pivotally attached thereto as at 32 the rod 33 connected at its opposite end to the transverse shaft 34 95 mounted upon either end in a sleeve 35, each slidably carried upon its respective rod 36. These rods are mounted at their upper ends in the hub-like depending portions 37 in the outboard end of the carriage 3, and at their 100

opposite ends through the pivotal shaft 30 of the arm 29, which, as before stated, is mounted in the lowermost extremity of the carriage 3. Beyond the shaft 30 and about each rod 36 is an expansive spiral spring 38 impinging against a suitable washer 39 adjacent the shaft 30 at one end and a set collar 40 about each shaft 36 at the opposite end.

About each rod 36 and centrally thereof is attached a set collar 41 which may be adjusted to any desired position for gauging the tension of the springs 38 in respect to the trigger 23, as it will be noted that said trigger is provided with inverted U-shaped extremities 42 surmounting the rods 36, and were not such tension covered by the position of the set collars 41 or otherwise it is evident that draft upon the line 20 would cause the trigger 23 to engage the sleeves 35 producing a pull on the rods 33 and tripping the bucket doors; it being seen by this novel toggle connection of bucket doors that once closed they are so biased, the center of the shaft 27 being forwardly of the center of the shaft 30, which forms the pivotal point of the lever 29. However, by the proper adjustment of the set collar 41, it is evident that the doors of the bucket may be made to remain closed at all times during any normal stress upon the line 20 in causing the bucket to travel inwardly towards the machine, but wherever desired, any sudden stress upon the line 20 to overcome such cushioning of the door lock will cause same to instantly open.

The depending door operating arms 28 are pivotally connected as at 43 to the head 44 through which the door rods 45 are mounted, they having expansive spiral springs 46 about their upper ends between their holding nuts and the head, so as to provide sufficient resiliency for same, while their opposite ends are attached to the doors 47, these latter being semi-circular to coincide with the circular bucket 50, as such is preferred to any other form of bucket, the tendency of concrete to stick being reduced to a minimum in such form of bucket. Furthermore this novel arrangement of bucket door suspension provides for one door hanging considerably lower than the other, as clearly illustrated in Figure 7, to act as a spreader or scraper for the contents as it leaves the bucket.

Just below the pivotal connection 4 of the boom 1 to the front of the paver are mounted two arcuately shaped fingers or arms 48, they being spaced apart so as to receive upon the concaved edges thereof the rollers 49 upon the extreme outer ends of the shaft 27 which forms the pivotal connection between the bucket arms 28 and the lever 29. By this means when the open bucket is brought inboard to its filling position the shaft 27 will be raised by virtue of the rollers sliding up

the arcuate arms 48 with the doors locked when the bucket is home, as shown in Figure 3 of the drawings, this simple form of toggle lock being old in the art.

The operation of the device is as follows:

Assuming the bucket as being loaded, and in its inboard or loading position, the arcuate arms 48 having lifted the shaft 27 by engagement with the rollers 49 on the ends thereof, to its locked position, as previously described, to wit: the shaft 27 being beyond the shaft 30 which forms the pivotal connection of the lever 29, so that the doors of the bucket will remain normally closed. Stress is then applied to the line 15, and the bucket and carriage drawn to any desired position on the boom, where, when it is desired to dump the bucket, sufficiently sudden stress is put upon the line 20 which tends to pull the carriage backwardly simultaneously with applying draft on the crosshead trigger 23 which latter stress is toward unlocking the lever 29 and if sufficient to overcome the tension of the springs 38 and the overbalanced weight upon the upper or free end of the lever 29, as previously described, the doors of the bucket will be opened. Whereas, if it is desired only to move the bucket backwardly without dumping only sufficient stress for such purpose is applied, as it is obvious that opposite stress of the operating mechanism whether the bucket is traveling in either direction will cause the same to dump.

From the foregoing it is evident that I have produced a comparatively simple and positive bucket control operated by two distinct and separate lines, and one that permits of free optional control of the bucket either in its opened or closed position.

Having thus described my invention, what I claim and desire to secure by Letters Patent, is:

1. The combination with a device of the character described including a boom, a carriage mounted upon the boom, a bucket carried by the carriage, and lines for operating the carriage, of means whereby opposite stress upon the lines opens the bucket, said means comprising a bracket depending from the carriage, an arm pivotally mounted with in the bracket the outboard end of said arm having limiting means attached thereto and the inboard end of the arm being operated by spring controlled means directly connected to one of the lines, and door controlling means attached to the outboard end of said arm.

2. The combination with a device of the character described including a boom, a carriage mounted upon the boom, a bucket carried by the carriage, lines for operating the carriage, and means carried by the carriage whereby one of the lines may be made to open the doors of the bucket, said means comprising a pivotally mounted trigger intermediate

of the ends of which the bucket operating line is attached and the free end of which trigger indirectly opens the door of the bucket, and means including resilient members whereby motion of the trigger is indirectly imparted to the doors of the bucket in opening same.

3. A bucket suspension of the character described comprising a horizontally reciproitable carriage, a depending frame structure carried thereby, arcuately shaped bucket supporting arms depending from the frame of the carriage and rigidly fixed thereto and the bucket, a pivotally mounted suspension for the doors of the bucket carried by the carriage frame, said suspension comprising an arm to the outboard end of which the doors of the bucket are indirectly attached, a cross-head trigger and spring controlled reciprocal guides therefor within the frame of the carriage connected with the inboard end of the door operating arm.

4. A concrete distributing mechanism comprising in combination a bucket carrying carriage, mechanism within the carriage for operating the doors of the bucket, a line for operating the carriage in one direction, a second line for operating the carriage in the opposite direction and being directly connected to the bucket door operating mechanism, said connection being spring controlled and including spaced reciprocal rods optionally operated by the action of the line.

5. A bucket door operating mechanism comprising a crosshead trigger, spaced rods operable by the free ends of the trigger, link mechanism for the doors of the bucket, a rod connected to the link mechanism and slidably mounted upon the trigger operated rods, a line connected to the trigger for optionally opening the doors of the bucket, and tension means carried by the rods for imparting opposite stress upon the trigger to that upon the line.

6. In combination a reciprocal carriage, a bucket suspended therefrom, doors for said bucket, link operating mechanism for said doors, spaced reciprocal rods carried by the carriage, a rod for operating the link mechanism reciprocably mounted upon the spaced rods, a crosshead trigger for reciprocating the spaced rods, spring controlled means for holding the spaced rods against action by the crosshead trigger, a line for operating the carriage in one direction and optionally operating the trigger against the action of the spring controlled means, and a second line for operating the carriage in the opposite direction.

7. A carriage and bucket door operating mechanism of the character described comprising a bucket carried by the carriage, a spring retained trigger carried by the carriage, spaced rods operable by the trigger, link mechanism for the doors of the bucket,

a rod connected to the link mechanism and mounted upon the trigger operated rods, a line directly connected to the trigger for optionally operating the carriage or opening the doors of the bucket by draft sufficient to overcome the action of the spring which retains the trigger.

8. A dumping mechanism for traveling buckets comprising a cross head trigger, link mechanisms connecting the doors of the bucket with the trigger, an operating line connected to the trigger for optionally opening the doors of the bucket or operating the latter, and adjustable tension means on said link mechanism whereby the stress on the trigger for dumping operation may be controlled.

In testimony whereof I hereunto affix my signature.
